US0D1007474S

(12) **United States Design Patent** (10) **Patent No.:** **US D1,007,474 S**
(45) **Date of Patent:** **** Dec. 12, 2023**

(54) **REMOTE CONTROLLER**

(71) Applicant: **Mitsubishi Electric Corporation**,
Tokyo (JP)

(72) Inventors: **Satoshi Arai**, Tokyo (JP); **Hiroichiro Shimano**, Tokyo (JP); **Yuki Motomura**,
Tokyo (JP)

(73) Assignee: **Mitsubishi Electric Corporation**,
Tokyo (JP)

(**) Term: **15 Years**

(21) Appl. No.: **29/762,883**

(22) Filed: **Dec. 18, 2020**

(30) **Foreign Application Priority Data**

Jun. 18, 2020 (JP) ..... 2020012104 D
(51) **LOC (14) Cl.** **14-03**
(52) **U.S. Cl.**
USPC **D14/218**
(58) **Field of Classification Search**
USPC D10/50, 65, 49, 104.1, 106.1, 106.95;
D13/162-172; D14/341, 374, 375, 389,
D14/126, 125, 315, 335, 371, 373, 318,

(57) **CLAIM**

The ornamental design for a remote controller, as shown and described.

DESCRIPTION

FIG. 1. is a perspective view of the front, right, and bottom sides of a remote controller showing our new design;

FIG. 2. is a front view thereof;

FIG. 3. is a rear view thereof;

FIG. 4. is a top plan view thereof;

FIG. 5. is a bottom plan view thereof;

FIG. 6. is a right side view thereof; and,

FIG. 7. is a left side view thereof.

The broken lines shown represent portions of the remote controller that form no part of the claimed design.

1 Claim, 7 Drawing Sheets
